[57] CLAIM

The ornamental design for a bottle or similar article, as shown and described.

DESCRIPTION

FIG. 1 is a perspective view of a bottle or similar article showing my new design;

FIG. 2 is a side elevational view on an enlarged scale, the opposite side being a mirror image of the side shown;

FIG. 3 is an elevational view looking from the left of FIG. 2;

FIG. 4 is an elevational view looking from the right of FIG. 2;

FIG. 5 is a top plan view; and

FIG. 6 is a bottom plan view.

FIG. 1
